CLAIM

I claim the ornamental design for a rocking chair, as shown and described.

DESCRIPTION

FIG. 1 is a top, front and right side perspective view of a rocking chair; showing my new design in full lines; FIG. 2 is a side view thereof;

FIG. 3 is a top view thereof;

FIG. 4 is a front view thereof;

FIG. 5 is a rear view thereof;

FIG. 6 is a cross-section view taken along line 6—6 of FIG. 4; and,

FIG. 7 is a cross-section view taken along line 7—7 of FIG. 4.
